UNITED STATES PATENT OFFICE

2,578,577

VAPOR EXPULSION

George C. Morris, Owosso, Mich., assignor to Redmond Company, Inc., Owosso, Mich., a corporation of Michigan

Application September 22, 1948, Serial No. 50,627

3 Claims. (Cl. 123—41.86)

1

This invention relates to vapor expulsion, and particularly to the expulsion of harmful vapors from the crankcase of an internal combustion engine.

Most of the automotive engine crankcase scavenging systems now in use operate on a theory that sufficient ventilation of the crankcase will occur if there is provision for entrance of air through a breathing pipe leading to the crankcase, and for emergence of air through a vent opening at some other point of the crankcase; the breathing action being usually dependent upon the draft created by the engine cooling fan, by pressure differentials existing between the inlet and outlet points, or simply upon the draft due to motion of the vehicle itself.

All these presently used arrangements tend to fall short of complete, effective scavenging action, mainly because they are not capable of maintaining a proper air pressure at the air entrance pipe under all conditions. A number of factors work against maintenance of proper air pressure at this point. A principal factor is the "blow-by" rate, that is, the rate at which air and gases penetrating into the crankcase from the combustion spaces tend to leave the crankcase by way of the air intake pipe rather than by way of the normal outlet vent, or "road tube." During idling of the engine, and in fact up to speeds of fifteen or more miles per hour, the volume of air "blow-by" escaping through the air intake tube may be greater than that escaping by way of the road tube. This sets up a reverse pressure condition at the intake tube and interferes with, or actually prevents, any intake of scavenging air during the persistence of such "blow-by" action.

The present invention aims to overcome this reverse flow condition in the air intake tube as well as other objectionable conditions, by providing a uni-directional pressure gradient at the air intake tube, which uni-directional pressure gradient will always be sufficient to defeat any tendency of the "blow-by" gases to escape from the crankcase by way of the air intake tube, thus forcing such gases to emerge by way of the vented road-tube, along with all the scavenging air.

An object of the invention, therefore, is to provide a novel combination of means for a more effective expulsion of harmful vapors from an engine crankcase under a variety of conditions encountered on one occasion or another during use of an automotive vehicle equipped with an internal combustion power plant.

A more specific object of the invention is to provide, in a scavenging system of the charac-

2

ter indicated, a substantially constant delivery of scavenging air to the crankcase, regardless of operating conditions.

Another object is to provide a novel combination and inter-relationship of air cleaner, impeller, driving motor, and oil receiving tube, with the three units first-named being carried directly upon the last named unit and co-operating therewith to provide the constantly effective uni-directional pressure gradient above described.

These and other objects of the invention will be better understood upon reference to the accompanying drawings illustrating one possible application of the invention. It is to be understood, however, that the accompanying drawings and the following explanation thereof, merely exemplify the invention without attempting to indicate its scope or limits. For a definition of scope and limits, reference is to be had to the appended claims.

In the drawings:

Fig. 1 is an elevation and partly sectional view of a unitary structure including an air cleaner, 25 impeller, and driving motor, all mounted on the oil receiving tube of an internal combustion engine; and

Fig. 2 is a top plan view, in part, and a sectional view, in part, of the assembly of Fig. 1.

In Fig. 1 the air cleaner is shown at 5, the impeller at 6, the driving motor at 7, and a mounting strap at 8, the latter embracing the oil receiving tube 9 for the crankcase and having its ends secured by screw 10. The upper edge of 35 the strap fits snugly against the under surface of plate 11 of the housing of impeller 6, and when in position it automatically locates prongs 12, 13 in registry with the aperture 14 in the wall of tube 9. The installation mechanic can then 40 insert a tool in the tube, through its upper end and bend these prongs back into engagement with the inner wall surface, thus causing these prongs 12, 13 to supplement the holding action of strap 8.

Motor 7 has an extending armature shaft 16 to which the hub 17 of the impeller 6 is secured for rotation therewith; the impeller having its blades so disposed, and the impeller chamber being so shaped, as to produce a rate of air delivery to tube 9, by way of aperture 14, that will be sufficient, at all different speeds, to maintain the desired unidirectional pressure gradient above described.

Air enters the cleaner 5 and passes through 55 the filtering material on its way to the blower

chamber. The latter is scroll-shaped, but has an abutment 21 to restrict somewhat the tendency to tangential flow and thus build up and maintain the desired pressure gradient, along the path of delivery to the tube 9. It will be understood that the tube 9 communicates at its lower end with the interior of the engine crankcase in the manner illustrated, by way of example, in Fig. 4 of my copending application No. 30,961, filed June 3, 1948; the tube 9 of the present disclosure being in this respect a counterpart of the tube 19 of said copending application.

Although the foregoing description includes details of but a single embodiment, it should be understood that the invention may be embodied in other arrangements of the component parts, and that certain component parts may be used independently of others, or with modifications thereof, within the scope of the invention as disclosed and claimed.

What I claim is:

1. In an internal combustion engine having a crankcase equipped with air intake and exhaust tubes for the circulation of scavenging air therethrough, said exhaust tube serving as a vent for such scavenging air and also as a vent for the "blow-by" entering the crankcase from the combustion spaces of the engine, means for maintaining the pressure in said air intake tube at a value that is always higher than the air pressure in said crankcase, to defeat any tendency of said "blow-by" to escape from the crankcase by way of said air intake tube, said pressure maintaining means comprising a motor-driven blower mounted on said air intake tube, a housing for said blower, and registering passages in said blower housing an intake tube for delivery of air to said intake tube, and said blower housing

including a wall running tangentially of the circular path described by the blower blades in rotation, said wall also turning sharply to form an air pocket tending to reduce the velocity and increase the pressure differential as the air stream enters said registering passages.

2. An air circulating system as defined in claim 1, wherein said blower housing further includes prongs projecting into the air intake tube along the bounding edges of said registering passages, to facilitate maintenance of proper registry between said passages.

3. An air circulating system as defined in claim 1, wherein said blower housing further includes a plate extending transversely between the blower and driving motor, and supporting the latter in suspension thereon, and a mounting strap surrounding said motor and air intake tube, said strap having its upper edge fitting under said transverse plate to provide support for the motor-blower assembly.
